UNITED STATES PATENT OFFICE.

ROY L. LEACH AND ANDREW T. BEALL, OF SALEM, OHIO.

FORMALDEHYDE FUMIGATING APPARATUS.

1,073,913.

Specification of Letters Patent.

Patented Sept. 23, 1913.

Application filed January 22, 1913. Serial No. 743,607.

To all whom it may concern:

Be it known that we, ROY L. LEACH and ANDREW T. BEALL, citizens of the United States, residing at Salem, in the county of Columbiana and State of Ohio, have invented certain new and useful Improvements in Formaldehyde Fumigating Apparatus, of which the following is a specification, reference being had to the accompanying drawings.

This invention comprehends certain new and useful improvements in fumigating apparatus and relates more specifically to that class of fumigators in which formaldehyde solution is employed.

An object of the invention is to provide a fumigator having a removable container in which formaldehyde solution may be positioned below the surface of the suitable fluid within an outer member and a perforated cover through which the fumes may escape.

Another object is to construct a device of this character between the parts of which air tight connections will be formed, thus compelling the fumes to escape through the perforated cover.

Another object is to generally improve and simplify the construction of the device of this character and increase the efficiency and commercial value of the same.

With these and other objects in view, this invention consists of certain novel details of construction, combination and arrangement of parts to be hereinafter more fully described, claimed and illustrated in the accompanying drawings, in which—

Figure 1, is an elevational view of the complete device, parts of the tank and cover being broken away to clearly show the parts within said tank and cover. Fig. 2, is a horizontal cross sectional view through the cover. Fig. 3, is a horizontal cross sectional view through the container. Fig. 4, is a fragmentary top plan view, showing the bowed spring clamping member in position. Fig. 5, is a view similar to Fig. 4 with the bowed spring clamping member removed. Fig. 6, is a cross sectional view on the line 6—6 of Fig. 1. Fig. 7 is a fragmentary sectional view through the sleeve and the roughened portion of the spherical cover.

Referring more particularly to the drawings in which like reference characters designate corresponding parts throughout the

several views, 1 designates the tank which is preferably of cylindrical form and constructed of copper or other suitable material and provided with a convex bottom 2, the edge of which is flared outwardly of the tank 1 to form the supporting flange 4. The supporting flange 4, as shown, is provided with the spaced openings 5 to reduce the weight of the same without sacrificing the strength thereof and also for the purpose of allowing the fumes to find their way beneath the bottom 2, as will be later clearly understood.

It will be understood that the upper end 70 of the tank 1 is opened and the bearing rings 6 are positioned at the upper end of the tank, the lower ring 6 resting upon the knobs 7 secured upon the outer face of the tank at the upper end thereof and positioned at diametrically opposite points.

The knobs 7 may be secured to the tank 1 in any suitable manner and are provided with central openings to receive the inwardly directed lower ends 8 of the bowed 80 spring clamping member 9 around the central portion of which is secured the sleeve 10 to which the handle 11 is also positioned.

The formaldehyde container 12 is preferably of circular form in cross section and 85 tapered toward its upper open end while the lower end is closed and has the semi-spherical portions 13 pressed upwardly from its under face, to allow the formaldehyde resting upon the bottom of the container 90 to be more readily heated, as will be clearly understood. The container 12 is also preferably formed of copper or other heat conducting material.

The upper end of the formaldehyde container 12 is secured in the lower portion of the perforated spherical cover 14, the greatest diameter of which is greater than the diameter of the tank 1. The spherical cover 14 rests upon the bearing rings 6 and 100 is clamped upon said rings by means of the spring clamping member 9 engaged thereon, the sleeve 10 having a roughened under face 10' for engagement with the roughened depressed portion 15 upon the upper face of 105 the spherical cover 14, thus preventing movement of said cover. It will be understood that a lowermost portion of the spherical cover 14 depends into the upper end of the tank 1, as clearly shown in Fig. 1. 110 It will be understood that the lowermost portion of the spherical cover 14, within the

upper end of the tank 1, is not perforated, thus eliminating all possibility of the fumes entering the tank 1 and compelling said fumes to escape through the perforations in the spherical cover 14, above the tank 1.

The formaldehyde solution is placed in the container 12 through the feed tube 16 positioned vertically in the spherical cover 14 and having its lower end depending into 10 the container 12 while its upper end is secured in the upper portion of the spherical cover 14, said upper end being threaded as shown at 17 to receive the threaded plug 18 by means of which the upper end of the 15 tube may be closed.

When it is desired to use this device, the spring clamping member is disengaged from the spherical cover 14 and the latter removed, after which the tank 1 is filled 20 with boiling water to within a spaced distance of the upper end of the tank. The spherical cover 14 is then replaced and the clamping member 9 engaged with the same, the formaldehyde container 12 displacing 25 the water sufficiently to cause said water to rise to about the top of the tank. The screw plug 18 is then removed and a small quantity of formaldehyde solution poured through the tube 16 into the container 12, 30 about one-half ounce of formaldehyde solution being a sufficient amount for ordinary purposes. The screw plug 18 is then replaced and it will be understood that the fumes will readily escape through the 35 perforations in the spherical cover 14, completely filling the room or the inclosure in which the device is positioned and killing all germs therein.

It will be understood that during the 40 operation of properly placing the tank 1, removing the screw cap 18, placing the formaldehyde solution in the container 12 and replacing the screw cap 18, the temperature of the water will decrease to about 180 degrees. As the tank 1 and container 12 are 45 formed of copper or the like, and there is no means of escape for the air, the temperature of about 160 degrees will be maintained and the formaldehyde vapor delivered at a temperature which insures its ut- 50

most efficiency and the entire strength of the charge is delivered in from 15 to 20 minutes.

While we have shown the preferred embodiment of our invention, it will be understood that we do not wish to be limited to this specific form, as minor changes in the details of construction may be made within the scope of the appended claims without departing from the spirit of our invention. 55 60

What is claimed is:—

1. A disinfecting device comprising a tank, a container within the tank and having portions of its bottom pressed upwardly, a cover for the tank, the upper end 65 of the container being secured in the cover, means for forming an air tight joint between the cover and tank, and means carried by the tank for clamping the cover in position. 70

2. A disinfecting device comprising a tank, a spherical cover having a portion thereof positioned in the upper end of the tank, the remaining portion of the cover being perforated, means for forming air tight 75 connections between the cover and tank, a formaldehyde container suspended from the cover and within the tank, and means for securing the cover in position.

3. A disinfecting device comprising a 80 tank, a spherical cover for the tank, the greater portion of the cover being perforated, a formaldehyde container suspended from the remaining portion of the cover and having its reduced upper end secured in 85 said cover, a feed tube within the cover and depending into the upper end of the container, means for closing the upper end of the feed tube, and means for clamping the cover in position and preventing movement 90 of the same.

In testimony whereof we hereunto affix our signatures in the presence of two witnesses.

ROY I. LEACH.
ANDREW T. BEALL.
